Atty.

UNITED STATES PATENT OFFICE

JAMES P. QUAM, OF CHICAGO, ILLINOIS

LOUD-SPEAKER UNIT

Application filed October 20, 1928. Serial No. 318,690.

- This invention relates to a loud speaker unit and particularly to an electro-magnetic device which is adapted to be connected with electrical apparatus, such as radio receiving apparatus, to effect the movement of a vibrating member, such as a cone, whereby electrical vibrations are translated into atmospheric vibrations of such frequency that they are audible to the human ear.
10. It is an important object of the present invention to provide a device of the kind described which is strong and simple in construction and capable of being economically manufactured.
15. It is another important object of this invention to provide an electro-magnetic loud speaker unit which is of such construction that the armature air gap may be conveniently varied and at the same time permanently retained in a predetermined desired position.

It is another object of the invention to provide a device of the kind described wherein the position of the armature relative to the 25 pole pieces may be conveniently varied and also permanently retained and adjusted as desired.

It is another important object of this invention to provide a loud speaker unit of the 30 kind described wherein the permanent magnetic member is of generally horseshoe shape and is held in position by a clamping member which may be also adjusted to vary the relative positions of the poles of said magnetic member.

It is also an important object of this invention to provide apparatus of the kind described wherein laminated pole pieces are clamped to the permanent magnet and are of 40 such form that they also provide integral cores for the electro-magnetic coils.

Other and further important objects of this invention will be apparent from the disclosures in the specification and the accompanying drawings.

The invention (in a preferred form) is shown on the drawings and hereinafter more fully described.

On the drawings:

50. Figure 1 is a side elevation of a loud

speaker unit embodying the principles of this invention.

Figure 2 is a top plan view thereof.

Figure 3 is an enlarged fragmentary section with parts in elevation on the line 55 III-III of Figure 2.

Figure 4 is a section on the line IV-IV of Figure 3.

As shown on the drawings:

For purposes of illustration, I have chosen 60 a preferred embodiment of the present invention wherein the operating apparatus is supported on a suitable bracket 1 which may be secured directly to a loud speaker casing (not shown) or supported in a cabinet if desired by means of an angle bracket 2 to which said bracket 1 is secured.

Secured to and projecting laterally from the bracket 1 are a pair of threaded studs 3 and between these studs is positioned a horseshoe magnet 4, the poles or free ends of which may be drawn toward each other in a manner which will now be described.

Engaged over the ends of the studs 3 outside of the outer leg of the horseshoe magnet 4 is a spanner plate 5 which is apertured for free engagement over said studs and which is clamped against the outer face of said outer leg of the horseshoe magnet by suitable nuts 6. Similarly engaging over the studs 3 and abutting the inner face of the inner leg of the horseshoe magnet 4 is a spanner plate 7 which is held in position against the inner face of said leg of the magnet by nuts 8 which like the nuts 6 are adjustable longitudinally 80 on the threads of the studs 3.

Supported on the inner faces of the legs of the horseshoe magnet member 4 at the free ends of said leg are laminated pole pieces 9 which are preferably formed of angle shaped laminations of high silicon steel, the laminations being angle shaped to afford lateral inwardly projecting portions 9a which afford cores of solenoids 10 the windings of which are connected in series with the electrical circuit output terminals of the instrument with which the unit of this invention is designed to cooperate. Connections from said circuit to the series winding of said solenoids are shown at 11 in Figure 4. The pole pieces 9 90

are secured to the legs of the horseshoe magnet 4 by suitable clamping means comprising apertured clamping bars which engage the outside of the legs of the magnet 4 and 5 the inner faces of the vertical portions of the pole pieces, said clamping bars being designated respectively by the reference numerals 12 and 13 and being secured together in the desired clamping relation by bolts 14 which 10 engage through the apertures in the clamping bars on either side of the legs of the magnet 4 and which are secured in adjusted position relative to said bars by means of nuts 15.

The armature of the unit of this invention 15 which is actuated by the magnetic fluctuation brought about by the flow of varying current through the solenoids 10 comprises a generally triangular shaped piece of relatively rigid silicon steel 16 which is ribbed vertically as 20 at 16° to afford additional rigidity without adding appreciably to the weight thereof. The lower corners of said armature 16 are provided with generally vertical slots 17 which are open at their lower ends to permit 25 engagement over the studs 3 so that the armature 16 is supported by said studs. Due to the relative longitudinal movement permitted by the open end slots 17, it is obvious that the armature 16 may be adjusted vertically relative to the studs 3 and when the desired vertical adjustment is attained, it is clamped in position relative to the studs 3 by means of suitable nuts and washers 18 and 19 mounted on said studs.

30 It is furthermore obvious that the mounting of the armature 16 makes it possible to shift the same laterally by moving the nuts 18 and washers 19 longitudinally of the threaded studs 3 and consequently affords 35 means whereby the armature may be accurately centered between the ends of the pole pieces 9. The upper or free apex of the armature 16 is rigidly connected by a member 20 with a vibrating member 21 which is preferably constructed of phosphor bronze, and the fixed end of which is secured beneath the clamping plate 12 on the outside of the outer leg of the magnet 4. This member 21 is suitably connected to a cone member 22 so that 40 when the member 21 is vibrated due to its connection with the armature 16 through the member 20, the cone member 22 will also be vibrated and set up the desired atmospheric vibrations to make possible the translation of 45 electrical impulses carried to the solenoids 10 into audible atmospheric vibrations.

50 It is obvious from the foregoing that I have provided a loud speaker unit which is simple and durable in construction and which is susceptible of economical manufacture. These desirable results are achieved by the improved method of mounting the pole pieces and by the construction of the pole pieces from angular laminations which makes possible the use of integral laminations which

afford both the securing portion of the pole pieces and the cores of the solenoids. Furthermore, due to the improved mounting of the magnet 4 which is provided by this invention, it is possible to accurately and conveniently regulate the air gap between the ends of the pole pieces by tightening or loosening the nuts 6 on the studs 3. At the same time, as previously explained, the position of the armature relative to the air gap, both laterally and vertically, may be conveniently adjusted and securely locked in a desired position when it has been adjusted upon manipulation of the nuts 18 and the washers 19. All of these adjustments are simple, easily effected and do not get out of adjustment when once made. Furthermore, due to the possibility of making these rigid adjustments, I am able to employ a much smaller air gap than is usual in apparatus of this kind. I am further able to do this due to the fact that the construction of this invention permits of the use of a relatively rigid armature which is firmly held in a desired adjusted position.

55 I am aware that many changes may be made and numerous details of construction may be varied through a wide range without departing from the principles of this invention, and I therefore do not purpose limiting the patent granted hereon, otherwise than necessitated by the prior art.

90 I claim as my invention:

1. In a loud speaker unit, a supporting bracket, a pair of spaced threaded studs projecting laterally therefrom, a horseshoe magnet positioned between the studs, means threaded on the studs for securing the magnet in position relative thereto and for adjusting the relative spacing of the legs of the magnet, an armature supported by said studs and projecting between the poles of the magnet, pole pieces and solenoids carried by said magnet on both sides of the armature, a cantilever connector secured at one end to the outside of one leg of the magnet, and means rigidly connecting said connector with the projecting end of the armature.

100 110 115 120 125 130 105 110 115 120 125 130

2. In a loud speaker unit, a supporting bracket, a pair of spaced threaded studs projecting laterally therefrom, a horseshoe magnet positioned between the studs, means threaded on the studs for securing the magnet in position relative thereto and for adjusting the relative spacing of the legs of the magnet, an armature supported by said studs and projecting between the poles of the magnet, means threaded on the studs for adjusting the position of the armature, pole pieces and solenoids carried by said magnet on both sides of the armature, a cantilever connector secured at one end to the outside of one leg of the magnet, and means rigidly connecting said connector with the projecting end of the armature.

3. In a loud speaker unit, a supporting bracket, a pair of spaced threaded studs projecting laterally therefrom, a horseshoe magnet positioned between the studs, means threaded on the studs for securing the magnet in position relative thereto and for adjusting the relative spacing of the legs of the magnet, an armature adjustably supported by said studs and projecting between the poles of the magnet, and means threaded on the studs for securing the armature in vertical and lateral adjustment.
4. In a loud speaker unit, a supporting bracket, a pair of spaced threaded studs projecting laterally therefrom, a horseshoe magnet positioned between the studs, means threaded on the studs for securing the magnet in position relative thereto and for adjusting the relative spacing of the legs of the magnet, an armature supported by said studs and projecting between the poles of the magnet, pole pieces clamped to the magnet on both sides of the armature, solenoids carried by said pole pieces and connected in series with an outside electrical circuit, a cantilever connector secured at one end to the outside of one leg of the magnet, and means rigidly connecting said connector with the projecting end of the armature.
- 30 In testimony whereof I have hereunto subscribed my name at Chicago, Cook County, Illinois.

JAMES P. QUAM.
